corporation of Delaware

Application March 14, 1936, Serial No. 68,870

3 Claims. (Cl. 201—73)

This invention relates to resistance elements and more particularly to elements having a resistance surface applied thereto for use in variable resistance devices such as rheostats, radio 5 volume controls and the like.

An object of the invention is to produce an improved resistance element for a variable resistance device.

Other objects of the invention will be apparent from the description and accompanying drawing taken in connection with the appended claims.

The invention may be applied to resistance elements of the type comprising a disc, sheet or 15 ring of insulating material or of a conductive material having an insulating surface, the element in each case having a layer of resistance material coated on a surface thereof. The resistance surface may comprise a plurality of 20 layers of the same or of different composition applied to the base.

The invention accordingly comprises the features of construction, combination of elements, arrangement of parts, and methods of manufacture referred to above or which will be brought out and exemplified in the disclosure hereinafter set forth, including the illustrations in the drawing, the scope of the invention being indicated in the appended claims.

For a fuller understanding of the nature and objects of the invention as well as for specific fulfillment thereof, reference should be had to the following detailed description taken in connection with the accompanying drawing, in 35 which:

Figure 1 is a face view of a variable resistance device with its cover removed;

Figure 2 is a section on the line 2—2 of Figure 1 with the cover added;

Figures 3 to 7 inclusive illustrate different stages in the manufacture of a resistance element for the variable resistance device;

Figure 8 is a section of a finished resistance element on the line 8—8 of Figure 7;

Figure 9 illustrates a modified form of conductive terminal coating.

Figure 10 shows a further modified terminal coating; and

Figure 11 shows a modified form of resistance 50 element.

Like reference characters denote like parts in the several figures of the drawing.

While a preferred embodiment of the invention is described herein, it is contemplated that 55 considerable variation may be made in the

method of procedure and the construction of parts without departing from the spirit of the invention. In the following description and in the claims parts will be identified by specific names for convenience, but they are intended to 5 be as generic in their application to similar parts as the art will permit.

Referring to the drawing and particularly to Figures 1 and 2 the variable resistance device 20 comprises a base formed of two superimposed 10 discs 21 and 22 of insulation, such as fibre impregnated with a synthetic resin. Discs 21 and 22 each have suitable cut-out portions to accommodate other parts of the resistor structure. A metal cover or cap 19 is secured to the discs 21 15 and 22 by ears 19a and encloses the operating parts. A ring 23 of sheet insulating material is disposed on top of disc 22 and is provided with a surface of resistance paint.

A pair of conductive terminal coatings 25 and 20 26 are provided at the two ends of the resistance surface.

Terminal bolts 27 and 28 pass through ring 23 and base disc 22 and are in electrical contact with terminal coatings 25 and 26, respectively. 25 Terminal lugs 29 and 30 are secured by bolts 27 and 28, respectively, underneath disc 22 and project out beyond the base to provide for external circuit connections to the two ends of the resistance surface. Bolts 27 and 28 not only 30 serve as terminals but likewise clamp the ring 23 to base disc 22.

Discs 21 and 22 are clamped together at their centers by a metal bushing 32 which passes through these members and a metal disc 33 35 clamped against the back of disc 21 by bushing 32.

A metal contact ring 34 having an integral terminal lug 35 is mounted against the face of disc 22 within the resistance unit ring 23 and concentric therewith. Ring 34 is held in place by a rivet or eyelet 36 which clamps disc 21 and lug 35 together.

The variable contactor structure comprises a shaft 37 rotatable in bushing 32, a contact arm 45 40 secured to the end of shaft 37 on the face side of said resistance device, a sliding contactor 40 mounted on the end of said arm and adapted to slide on resistance surface 24 on ring 23, and sliding contact fingers 39 integral with 50 said arm and adapted to slide on contact ring 34. Shaft 37 is held against axial motion by clip washer 31 fitted in an annular groove in shaft 37 adjacent the rear end of bushing 32. Contact arm 38 is secured to the end of shaft 37 and in- 55

sulated therefrom by a small piece of sheet insulation 41 the end of said shaft being upset to hold said piece 41 in place. Contact arm 38 and piece 41 are clamped together by a rivet pin 42. Pin 42 has a projecting portion 43 for operating a switch element which may be secured to the cover, if desired, so that the switch actuating lever is engaged by projection 43. Arm 38 and contact fingers 39 are of spring construction 10 and are held in tension by clip washer 31 so that the sliding contact portions are held in contact with their respective ring surfaces.

In operation, the terminal lugs 29, 30 and 35 are connected into an external circuit in any desired manner. By turning shaft 37 with a knob or other control means sliding contactor 40 will slide on the resistance surface 24 in a circular path. Thus the length of the resistance path, and consequently the magnitude of the resistance 15 in series with terminal lugs 29 and 35 or 30 and 35 may be varied. Conductive coating 26 extends out a sufficient distance from terminal bolt 27 so that contactor 40 may ride up onto it as it approaches the terminal, thereby reducing the 20 resistance to a negligible value. This enables the turning of arm 38 for a few degrees at the end of the stroke to allow for a switch to be operated by projection 43 on pin 42, if desired, without varying the resistance. The contact arm 25 may be turned until it comes into direct contact with the screw 28 connected to lug 30, thereby reducing the resistance to substantially zero.

In most radio sets where resistance devices such as that just described are used for volume 30 control purposes it is preferable that the rate of resistance change with uniform rotation of the control shaft shall vary as a given function of the degree of rotation. The type of resistance vs. rotation curve will, of course, depend on the 35 particular circuit in which the volume control is used. The most generally useful curve is probably a logarithmic form of curve.

Resistance elements have been made by coating an absorbent paper disc with a layer of resistance material and then applying a second 40 layer in superimposed fashion over the first one for only part of the length of the resistance path. The units have then been rolled to create a smooth contact surface which would produce less noise in operation.

However, rolling does not distribute the resistance material and consequently such units 45 have had relatively abrupt "jump-off" characteristics at the ends of resistance layers with resultant noise in the electrical circuits. This had been particularly true with units having a base of hard material such as "Bakelite" fibre. With these units likewise the resistance vs. degree of rotation curves have only roughly approximated the preferred logarithmic curve.

According to one aspect of the present invention a resistance element may be produced which will provide a uniform resistance vs. degree of rotation curve of logarithmic or any other desired form and may be applied to a non-absorbent base as well as to bases of other types.

In accordance with a preferred method of making the resistance element, ring 23 of Bakelized fibre (see Fig. 3) is sprayed with resistance paint through suitable cut-out sheet metal 70 masks or stencils by well-known methods. The ring 23 is preferably made of a material which has a rather dull lusterless finish.

First a tapered low resistance layer 45 is sprayed onto the disc (Fig. 4).

If a second taper is required the mask is removed and another mask having the required taper openings is used. The second tapered layer 46 (Fig. 5) may preferably cover the first layer and extend beyond it for the required distance. 5 Additional tapers may be applied when required. Finally an overall coating 47 of resistance material is applied in the same manner resulting in the partially finished unit shown in Fig. 6.

After the final resistance coating is applied 10 low resistance terminal coatings 25 and 26, of a highly conductive material such as silver paint, are sprayed through a suitable mask onto the element. In applying this coating, however, the mask is spaced slightly above the surface to be 15 coated. This allows the spray to spread slightly after passing through the mask thereby producing a feather edge to the coating. This feather edge is desirable in that it prevents mechanical roughness and sudden jumps in the electrical 20 resistance when the sliding contactor is moved over the surface. A face view of the finished element is shown in Figure 7 and a section is shown in Figure 8 in which the thickness of the various 25 layers is greatly exaggerated.

A feature of the above element is that the softer lower resistance layers are put onto the base first and the harder high-resistance layers are applied over them and serve to protect the 30 softer layers from wear.

The paint for the low-resistance layer 45 may be composed of finely pulverized graphite suspended in denatured alcohol or synthetic alcohol or the composition may be varied to include a certain percentage of lampblack.

For the layer 46, which may preferably be of intermediate resistance, no silver powder is used and a higher proportion of shellac is used. Likewise the ratio of lampblack to graphite may be higher. The paints for other intermediate 40 layers, when provided, may have the ingredients variously proportioned to give the desired specific resistance. In general silver produces the lowest resistance, with graphite next and lampblack highest, the addition of shellac tending, in all 45 cases to increase the resistance.

For the top resistance layer 47 lampblack is used with a smaller proportion of graphite and a higher proportion of shellac. For applying all the layers sufficient solvent, such as denatured 50 alcohol, is used to obtain the desired viscosity for spraying. After drying, the top layer, with less graphite and more shellac, will be quite hard and wear-resistant and will protect the softer layers underneath. Similarly each layer, being harder than the ones beneath it, helps to protect the bottom layers.

The point used for the terminals 25 and 26 may be composed of the precipitated silver powder suspended in a shellac and alcohol solution.

Figure 9 shows a modified form of silver paint coating which may be applied either on top of or underneath the resistance layers. This coating includes a series of strips 48 of silver paint sprayed through a suitable mask, the resistance 65 material bridging the gaps between adjacent strips. Near the terminal portion 26 the strips 48 are radial but at the outer end they are skewed a certain amount so that the contactor will bridge two strips. This provides a low resistance taper.

Figure 10 shows another modification in which the strips of silver paint 48a are skewed near the terminal but are substantially radial at the outer end.

Figure 11 shows a modification in which a short 75

tapered low-resistance layer 49 is provided adjacent terminal 25 in addition to the tapers at the opposite end. Taper 49 serves to smooth out the change in resistance where the contactor leaves the carbon resistance surface and rides onto the silver terminal 25.

After the resistance and terminal paint coatings have been applied to the base discs they are dried and baked.

10 For applications where no switch is to be actuated by the control arm the silver paint terminal 26 can be shorter, that is, similar to terminal 25, since in this instance it is not necessary that the contactor move any great distance without 15 change in the resistance in the circuit. It is also obviously possible to vary the shape of tapers used and the relative lengths of the various resistance layers to obtain a resistance vs. degree of rotation curve of any desired shape. It will be 20 noted that the thickness of any layer is constant throughout its area but that it has a variable width due to the taper, which preferably comes to a point along the middle of the resistance surface.

The life characteristics of the finished units 25 are extremely good. With volume control devices having resistance elements made according to the present invention it has been found that 60,000 rotations of a contact arm forth and back across the resistance surface (120,000 passes) 30 changed the resistance of the units by less than 5%. On humidity tests at 115° F. in air saturated with water vapor the resistance of a unit was changed less than 5% in 24 hours and the resistance was found to return to its original 35 value when the unit was allowed to stand in a normal atmosphere.

While the present invention, as to its objects and advantages has been described herein as carried out in specific embodiments thereof, it is 40 not desired to be limited thereby but it is intended to cover the invention broadly within the spirit and scope of the appended claims.

What is claimed is:

1. A resistance element for a variable resistance device comprising a base of insulating material having an elongated surface, a tapered layer of resistance material on said surface, the base of said taper being adjacent one end of said 5 surface and the point of said taper being intermediate the ends of said surface, and a second tapered layer of resistance material superimposed on said first layer with its base over the base of said first layer and its point beyond the point of 10 said first taper.

2. A resistance element for a variable resistance device comprising a base of insulatory material having a relatively smooth surface, a pair of spaced conductive terminals on said surface, a 15 layer of electric resistance paint on said surface in a path extending between said two terminals, said layer comprising a first area adjacent and in contact with one of said terminals which is of paint of a certain specific resistance, said area 20 tapering to a point intermediate said terminals and the rest of said resistance path being of paint of a higher specific resistance and contacting the other of said terminals.

3. A resistance element for a variable resistance device comprising a base of insulatory material having a relatively smooth surface, a pair of spaced conductive terminals on said surface, a layer of electric resistance material on said surface in a path extending between said two terminals, said layer comprising a first area adjacent and in contact with one of said terminals which is of a certain specific resistance, said area tapering to a point intermediate said terminals, a 25 second area adjacent and in contact with the other of said terminals which is of a certain specific resistance, said second area tapering to a point intermediate its contacting terminal and the point of said first area, and the rest of said resistance path being of higher specific resistance 30 than either said first or said second areas.
